ATTORNEY.

UNITED STATES PATENT OFFICE.

JOSEPH H. AMES, OF NEW YORK, N. Y., ASSIGNOR TO AMERICAN CAR AND FOUNDRY COMPANY, OF NEW YORK, N. Y., A CORPORATION OF NEW JERSEY.

ERECTION TRUCK.

Application filed May 17, 1922. Serial No. 561,645.

To all whom it may concern:

Be it known that I, JOSEPH H. AMES, residing at New York, county of New York, State of New York, and being a citizen of the United States, have invented certain new and useful Improvements in an Erection Truck, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

20 In said drawings:

Fig. 1 is a view in elevation, showing the manner of using my improved erection truck;

Fig. 2 is a plan view of my device, parts 25 being broken away to show other parts more clearly;

Fig. 3 is a section taken on the line 3—3 of Fig. 2;

Fig. 4 is a central vertical section showing 30 the driving dog which engages the conveyor chain in operative or engaging position;

Fig. 5 is a fragmentary section showing the dog in the inoperative or release position;

35 Fig. 6 is a section taken on the line 6—6 of Fig. 4; and

Fig. 7 is a section taken on the line 7—7 of Fig. 2 showing the manner of supporting a seat from the truck bolster.

40 It is an object of my invention to provide an improved truck upon which railway car bodies may be supported during erection. It is also an object of my invention to provide a truck of the type described de-

45 signed to be moved forward continuously by a chain conveyor or other suitable driving means during the construction of the car body supported thereon. It is also an object of my invention to provide a truck of 50 the type described that may be readily adapted to support bodies of different widths. It is also an object of my invention to provide a means for quickly engaging the truck with or disengaging it from 55 the driving means.

With these and other objects in view, my improved truck comprises a plurality of cast side frame members 1, of substantially I-beam shape at the center and having bifurcated ends formed of channel-shaped end sections 2 and seats 3 formed integral with the center portion of the side frame to accommodate a reduced end portion 4 formed on a cast bolster member 5. The bolster is of substantially I-beam shape 60 and is secured to the side frames by the rivets 6. In bearings 7 formed in the end sections 2 there are mounted axles 8 which are secured in place by cotter pins 9 and have wheels 10 journaled thereon. The 70 outer ends of the end sections 2 at each end of each side member 1 are joined by channel-shaped end members 11 secured to flanges 12 formed on the end sections 2. To the bottom flanges of the end members 75 11 at the front of the truck there are secured brushes 13 which serve to remove small obstructions from the rails 14 on which the wheels 10 travel. Wheel covers 80 15 are secured to the end sections 2 and the upper flanges of the end members 11 and prevent small objects from falling into the wheel openings.

The bolster 5 is provided at its center, adjacent to its upper flange, with a bearing 85 16 to receive a pin 17 which secures a cast center pedestal 18 to its seat on the upper flange of the bolster 5. The upper end of the pedestal 18 is formed with a flat face having a central circular opening adapted 90 to receive the cylindrical shank 19 formed on the center plate 20. The center plate 20 is shaped to conform to the work it is intended to support and is detachably and rotatably held in the opening in the pedestal 18 by pin 21 which engages in co-operating grooves formed in the shank 19 and in the wall of the opening in the pedestal.

Adjacent each end of the bolster 5 a 100 side pedestal 22 is secured to its seat on the upper flange of the bolster by a pin 23 which has a bearing, not shown, in the bolster similar to the bearing 16. Each pedestal 22 is provided at its top with an 105 opening to receive the shank 24 of a side bearing 25, the side bearing 25 being detachably secured in the opening by a pin 26 which passes through the shank 24 and the walls of the opening in the pedestal. 110

The side bearings 25 are mounted eccentrically upon their shanks 24 as illustrated in full lines in Fig. 3, and adapted to be turned laterally to the position indicated in dotted lines in Fig. 3, if it is desired to extend the supporting area of the bearings to provide a wider support for the work carried by them. Bearings of different heights are provided and are substituted when necessary to properly support the work.

On the forward side of the web of the bolster 5 there is mounted a bracket 27 for supporting a collapsible driving mechanism. The bracket is provided with a pair of projecting arms in which is mounted a pin 28 having a driving dog or puller 29 pivotally mounted thereon. The dog 29 is long enough to project into a slot formed in the floor and engage with the links of a chain conveyor 30 that is driven by any suitable means and at a suitable speed. The dog 29 has formed integral therewith a hook 31 adapted to be engaged by a latch 32, secured to bolster 5 by eye-bolts 33, when the dog 29 is raised to the release position as shown in Fig. 5. Mounted in the dog 29 is a pin 34 upon which an operating handle 35 is pivotally mounted, the handle 35 being kept from engagement with the floor by a support 36 secured to the lower flange of the bolster 5. There is also pivotally mounted on the pin 34 a yoke 37 having a flat strap-like portion 38 adapted to project through an opening 39 in the web of the bolster 5 and to rest upon the bottom flange of the bolster when the dog 29 is in position to engage the chain 30. The strap-like portion 38 is provided with a tapered projection 40 adapted to engage with the bottom flange of the bolster 5, the outer edge of the bolster flange having a portion provided with an inclined surface to engage with the inclined surface of the projection 40. Yoke 37 is held in operative engagement with the lower flange of the bolster 5 by a locking cam 41 moving between the arms 43^a of bracket 43 secured to the web of bolster 5. The locking cam is fixed to a transverse shaft 42 having a bearing in the arms 43^a of bracket 43 and also journaled in bearings 44 on the side frame members 1. The shaft is fitted at its ends with operating handles 45 which are limited in their movement by means of the stop lugs 46 on the side frames.

For some of the operations in the construction of car bodies it is desirable to have the workman travel with the truck so there is provided a seat support 47 upon which a seat 48 is adjustably mounted. The support 47 is provided with oppositely disposed projections 49 and 50 formed of pairs of metal strips secured together and to the support 47 and having their outer ends bent in opposite directions to form feet adapted to engage with the web and bottom flange,

respectively, of the bolster 5. As shown in Figs. 3 and 7, the end of the support 47 is passed through an opening in the bolster web so that the projection 49 engages with one side of the bolster web and the projection 50 engages with the bottom flange on the other side of the web.

In the construction of car bodies using my erection truck a pair of the trucks are placed on the erection track, spaced the proper distance for the reception of the frame members and the frame members rested thereon. The leading truck has its dog 29 placed in position to engage the conveyor chain 30 while on the other truck the dog 29 is held clear of the chain 30 by the latch 32, the second truck being pulled by the frame members carried thereon. To place the dog 29 in the engaging position, the latch 32 is disengaged from the dog 29 so that the dog 29 will take the position shown in Fig. 4 with the yoke 37 projecting through the opening 39 and the projection 40 in engagement with the bolster bottom flange. The locking cam 41 is then brought into engagement with the yoke 37 by the operation of the shaft 42 by the handle 45 so that the yoke 37 and projection 40 are locked in engagement with said bolster flange. It will be noted that the pull exerted by the dog 29 on the yoke 37 tends to operate the locking cam 41 to force the yoke 37 against the bolster flange. To disengage the dog 29 from the chain 30, the cam 41 is disengaged from the yoke 37 and the dog 29 raised by means of handle 35 until the latch 32 engages with the hook 31 as shown in Fig. 5. It will be noted from the foregoing that when two trucks built as described are positioned in spaced relation upon a straight track they provide complementary elements of a mobile erection bench having a variable supporting area for the accommodation of work of different length and width. It will also be noted that low side frames of the individual trucks and the relatively high work-supporting pedestals and the use of short axles provide ample room for the operations of the workmen at the truck positions.

What I claim is:

1. In a truck, spaced side frames, a bolster connecting said side frames, a driving dog for the truck carried by said bolster, a latch carried by said dog for engaging the bolster and holding the dog in an operative position, and means carried by the bolster for securing the dog in operative engagement with the bolster.
2. In a truck, spaced side frames, a bolster connecting said side frames, a driving dog carried by said bolster and means carried by said driving dog for engaging said bolster and holding the driving dog in operative position.

3. In a truck, spaced side frames, a bolster connecting said side frames, a driving dog carried by said bolster, means carried by the bolster to hold said driving dog in an inoperative position, means carried by said dog for engaging the bolster and holding the dog in an operative position, and means for engaging the last mentioned means and retaining the same in operative engagement with the bolster.

4. In a truck, spaced side frames, a bolster connecting said side frames, a driving dog carried by said bolster, a yoke connected to said dog and means to engage said yoke to hold said dog in operative position.

5. In a truck, spaced side frames, a flanged bolster connecting said side frames, a driving dog carried by said bolster, means connected to said driving dog adapted to engage said bolster flange and means to hold said first mentioned means in engagement with said flange.

6. In a truck, spaced side frames, a flanged bolster connecting said side frames, a driving dog carried by said bolster, a yoke connected to said driving dog and adapted to engage said bolster flange and a locking cam adapted to lock said yoke in engagement with said flange to hold said driving dog in operative position.

7. In a truck, spaced side frames, a flanged bolster connecting said side frames, a driving dog carried by said bolster, means connected to said driving dog and adapted to engage said bolster flange, a locking cam

adapted to lock said means in engagement with said flange to hold said dog in operative position, means to operate said locking cam and means to hold said dog in inoperative position.

8. In a truck, a driving dog adapted to drive the truck, means carried by said dog for engaging the bolster and holding said driving dog in operative position, and releasable means for retaining the first means in engagement with the bolster, the first mentioned means when released from the second means being adapted to release said dog while said dog is driving the truck.

9. In a truck, a bolster, a driving dog carried by said bolster and means carried by said dog for engaging said bolster and securing the dog in position to drive the truck, said means being adapted to release said dog while said dog is driving the truck.

10. In a truck, spaced side frames, a bolster connecting said side frames, a driving dog carried by said bolster, a yoke connected to said dog and adapted to engage said bolster and means to hold said yoke in engagement with said bolster to hold said driving dog in operative position, said means being adapted to release said yoke from engagement with said bolster and permit said dog to move to the inoperative position while said dog is driving the truck.

In witness whereof I have hereunto set my hand.

JOSEPH H. AMES.
